(57) CLAIM

The ornamental design for baseball decanter set, as shown and described.

DESCRIPTION

FIG. 1 is an exploded isometric view of baseball decanter set showing my new design;

FIG. 2 is a front exploded elevational view thereof of FIG. 1;

FIG. 3 is a rear exploded elevational view thereof of FIG. 1; FIG. 4 is a right side exploded elevational view thereof of FIG. 1;

FIG. 5 is a left side exploded elevational view thereof of FIG. 1;

FIG. 6 is a top plan exploded view thereof of FIG. 1;

FIG. 7 is a bottom plan exploded view of thereof of FIG. 1.

FIG. 8 is an isometric view of thereof of FIG. 1;

FIG. 9 is a front elevational view thereof of FIG. 1;

FIG. 10 is a rear elevational view thereof of FIG. 1;

FIG. 11 is a right side elevational view thereof of FIG. 1;

FIG. 12 is a left side elevational view thereof of FIG. 1;

FIG. 13 is a top plan view thereof of FIG. 1; and,

FIG. 14 is a bottom plan view of thereof of FIG. 1.

The broken lines are included for the purpose of illustrating features of the baseball decanter set that form no part of the claimed design.
